John C. Richard, of New York, N.Y.

Letter Patent, No. 2053. Dated April 11th, 1865.

Design for a Trade Mark.

The schedule referred to in this Letter Patent and making part of the same.

To all whom it may concern:

Be it known that I, J. C. Richard, in the city and county of New York, and State of New York, have invented or produced a new and ornamental design for a Trade Mark, for Lead Pencils, and for Packages or Boxes for the same: and I hereby declare that the following is an exact description thereof, prepared with a view to the obtaining of Letter Patent therefor.

The accompanying drawing represents my design on a large scale. My design is composed of the shield from the American Coat of Arms with the word "American" in close proximity thereto, so as to form part of the same design.

The outline of the shield is formed by four curves, two forming the upper steps, and the others forming the curved and inclined sides, so as to give the general outline approximating to a triangular or heart shape. There are thirteen vertical stripes, alternately dark and light, which fill the lower half of the shield. The upper half contains stars as represented. The word "American" I make in plain Roman capitals, as represented.

In affixing this trade mark upon pencils, I prefer to bronze or gild the impression by the ordinary well known means. In affixing it upon packages or boxes for pencils, I may print it in bronze or in ink, either black or colored.

Claim.

What I claim and desire to secure by Letter Patent, is the design for Trade Mark herein described, composed of the shield from the American Coat of Arms, and the word "American" in close proximity, as shown.
